TUBULAR METAL STAY FOR MOLES
 Louis Alzari, 25 Boulevard Carabacel, Nice,
 Alpes-Maritimes, France
 Filed July 2, 1962, Ser. No. 206,843
 Claims priority, application France, July 7, 1961,
 6,892, Patent 1,294,479
 7 Claims. (Cl. 25—131.5)

My invention has for its object an arrangement for staying molds or the like structure during the erection of a building. Although said arrangement may receive other applications, it is particularly suitable for staying the structures simultaneously at two different levels as in the case of floors made of reinforced concrete and incorporating visible beams in which case it is necessary to stay simultaneously the lower surface of the mold and the sides of the beam with reference to the upper surface of the floor.

According to my invention, I resort to a stay including a metal tube provided with openings distributed at different levels, a cross-member adapted to slide freely over said tube and guided by it, while a sleeve may be shifted along said tube and be keyed thereto by means of a spindle passing through one of the openings of the tube and lastly, means for gradual adjustment fitted between the sleeve and the cross-member to define the height of the latter, said means including preferably a tubular member coupled threadedly to the sleeve and carrying the cross-member. It is thus possible to adjust vertically the position of the cross-member with reference to the central stay first in an approximate manner through selection of the opening in the tubular stay in which is fitted the pin which is to hold the sleeve in its vertical position and then in a more accurate manner, by screwing the intermediate member carrying the cross-member over the sleeve.

In the accompanying drawing illustrating my invention, FIGS. 1, 2 and 3 are an elevational view, an axial cross-section and a plan view of a first embodiment.

FIGS. 4 and 5 are a front view and a side view of a simplified embodiment.

FIGS. 6 and 7 illustrate the positioning of an edge plank against a supporting wall according to conventional methods and with my improved stay respectively.

FIG. 8 illustrates diagrammatically the making of a concrete floor according to conventional methods.

FIG. 9 shows a manner of making such a floor with the arrangement according to FIGS. 1 to 3.

FIG. 10 shows a stay designed for the making of visible beams.

FIG. 11 is an elevational partly sectional view of a further arrangement for the making of visible beams in a floor.

FIG. 12 is a sectional view through line XII—XII of FIG. 11 after removal of the molding parts.

FIG. 13 is a cross-section of the cross-member through line XIII—XIII of FIG. 12, and

FIG. 14 is a partly sectional end view of said beam.

Turning to FIGS. 1 to 3, the tubular metal stay 1 is provided with vertically spaced openings 2 and it carries a freely slideable sleeve 3 which may be secured approximately at the desired level by a transverse cotter 4 passing through an opening in the sleeve and the selected opening 2 in the stay. The sleeve 3 is sufficiently long for it to be closely guided and it is provided near its upper end with an outer thread 3' over which is screwed a tubular nut-shaped member 5 which may be readily turned through action on its lugs 5'.

The flanges of the cross-member 6 formed by a channel iron bent over the upper edge of the tubular nut 5. To said cross-member (FIG. 3) is welded or otherwise

2

secured between the flanges of said cross-member a collar 7 the inner diameter of which is such that it may slide freely with a minimum clearance over the stay 1. It will be readily ascertained that such an assembly allows an accurate adjustment in position of the cross-member 6 through the nut 5 in spite of the comparatively large spacing between the openings 2 which serve for defining at the start the position of said cross-member while a rigid fitting of the cross-member in its adjusted position is ensured by the collar 7. Furthermore, the cross-member which may extend to one side or to both sides of the stay may revolve freely round the latter which furthers its use for all applications.

The upper end of the upright is provided with the usual capping plate 8 projecting to one side.

FIGS. 4 and 5 show a simplified arrangement wherein the sleeve 3a is provided with a number of openings, the spacing between which is reduced and which are distributed in staggered formation along a number of superposed lines 2a, 2'a so as to allow securing the sleeve through a transverse pin to the stay at a level approximating the desired level. Said sleeve is provided at its upper end with an outer horizontal flange 3" the upper surface of which is engaged by a wedge c fitted between said flange and the cross-member 6 whereby the latter may be adjusted in position and be set exactly at the desired level.

FIG. 6 shows how a stay A is conventionally erected in position adjacent a wall M and carries at the desired height with the interposition of a horizontal board H a vertical edge plank L carrying in its turn the horizontal edge plank R. To prevent any rocking of the latter, it is necessary to engage its free ridge by wooden members I which hold also in position the vertical edge plank L. The application to this case of an arrangement according to my invention as illustrated in FIG. 7 makes such a positioning of the edge planks an easy, speedy and reliable matter. Inspection of FIG. 7 shows that the upstanding edge planks L are automatically held in position between the wall M and the upper end of the stay 1 while the upper horizontal edge plank rests without rocking over the capping plate 8 of the stay, the whole arrangement being brought to the desired level in an accurate manner through adjustment of the sleeve 3 or 3a with reference to the stay.

My invention is particularly applicable to the case where it is desired to make a floor of reinforced concrete incorporating visible beams. At the present time, the fitting of the mold of such a beam is obtained as illustrated diagrammatically in FIG. 8 by laying a cross-member B over each of the stays S arranged in alignment and adjusted as to height and over the successive cross-members B there are laid the board C forming the bottom of the mold together with the mold sides DD which are further held by oblique wood ties B. All these adjustments are long and intricate, and are obtained much more easily, more speedily and more reliably through my invention.

Thus, FIG. 9 shows how it is possible to make use of the apparatus according to FIGS. 1 to 3. The tubular stays are arranged vertically pairwise, as shown at 1-1' to either side of the location of the beam to be obtained, said stays having their capping plates 8 flush with the lower ceiling-forming surface of the floor. Over the cross-members 6 which are brought to the accurate level required, there is laid the bottom board C of the mold and the lateral mold boards DD which rest thus on said cross-members 6 while the lateral boards bear laterally against the upper section of the tubular stays 1-1'. All the parts forming the mold are thus held rigidly in their accurate positions.

FIG. 10 shows a stay made according to the inven-

tion which is designed more particularly for the molding of visible beams in a floor, said stay being constructed almost entirely by metal parts and forming thus a fraction of a mold intended for the making of beams of various heights and breadths.

The metal side walls Da are carried by the cross-member $6a$ and held vertically by the ties Ea . Their spacing may be adjusted as required and to this end the lower end of each side wall is secured for instance at the desired point longitudinally of the cross-member as provided by a stud 10 formed on the side wall and entering one of a series of openings distributed along the upper surface of the cross-member. Furthermore, each tie Ea is pivotally secured at its upper end to the side wall and is provided with a series of openings distributed along its lower section so as to allow its securing to the cross-member by means of a pin. The bottom Ca of the mould is constituted by a board or plate the breadth of which corresponds to the spacing between the side walls Da and is carried by the capping plate $8a$ of the stay. Since said capping plate allows adjusting as desired and in an accurate manner the difference in level between the upper end of the stay and the cross-member $6a$, it is possible to make the improved stay according to FIG. 10, match all sizes and all cross-sections of beams and to allow the use of the adjusted stay for a metal mould which provides obviously all desired advantages of speed, accuracy and the like.

In the case of FIG. 10, it is necessary to make an opening of the sleeve register with the selected opening of the stay, so as to engage therein the locking pin, which operation is not always convenient and does not always allow a speedy operation. On the other hand, the lateral walls of the mould are not always held accurately at the desired spacing and their adjustment to a spacing corresponding to the desired breadth of the beam is obtained only approximately through stepwise operation.

FIGS. 11 to 14 illustrated an improved arrangement cutting out the drawbacks of the preceding arrangement and wherein the independent adjustment of the height of the cross-member above ground on the one hand and the height of the bottom of the mould with reference to the cross-member on the other hand and also the adjustment of the location and vertical position of the sides of the mould are obtained in a gradual and accurate manner.

In said figures, Sa designates the actual stay support standing on the ground whereas the horizontal capping plate $8a$ is carried by the actual tubular stay 1 sliding in said support Sa so as to be fitted therein at the desired level as provided by the following means: over the outwardly threaded upper end of Sa , is screwed a sleeve 11 over the upper end of which rests a pin 12 passing through the vertically adjustable stay 1 , so as to hold the latter in position.

The cross-member $6a$ is formed as fully apparent from FIGS. 12 to 14 by two angle bars 13 and $13'$ facing each other, said angle bars being notched in the medial section of their horizontal flanges and being welded both along said notches and along at least a part of their vertical flanges to a tube 14 extending between the latter and serving as a guide for the stay 1 over which said tube 14 is slidably fitted. Said tube 14 acts as an intermediate member between the actual cross-member $6a$ and the sleeve 15 screwed over the tube 14 so as to hold said cross-member at the desired approximative height. A securing pin 16 is inserted underneath said sleeve 15 in the desired opening of the stay 1 which is apparent to view, the sleeve being allowed to rest through the agency of a washer 17 on said pin 16 which is advantageously connected with the washer 17 by a small chain. This being done, the tapped sleeve 15 is rotated so as to be screwed over the outwardly threaded tube 14 whereby the height of the cross-member is adjusted independently of the adjustment of the level of the capping plate $8a$ rigid with the stay 1 .

To either side of their medial section carrying the tube 14 , the two angle bars 13 , $13'$ forming the cross-member $6a$ are separated by a gap or slot 18 or $18'$ inside which may slide a tapped member 19 or $19'$ (FIGS. 12 and 13) adapted to be locked in position by any suitable clamping means. I may resort for instance to a screw controlled by a handle 20 and provided with a nut 21 welded over its end and forming a stop, said screw engaging the tapped member 19 or $19'$ so as to clamp the edges of the angle bars 13 and $13'$ between a shoulder formed on said member and a washer 22 resting on the nut 21 . The members 19 and $19'$ serve for wedging in position, directly or through the agency of wooden blocks 23 , the lower ends of the sidewalls 24 and $24'$ of the mould.

With a view to locking also in position the upper ends of said sidewalls, I have provided the following arrangement: towards each of their ends, the angle bars 13 and $13'$ carry extensions formed by two shaped members $25a$, $25b$ spaced with reference to each other and leaving between them as shown in FIG. 14, a gap i which by reason of the elasticity of the metal may close slightly under the action of a screw controlled by a handle 26 and engaging a nut 27 held against rotation; on the other hand, the upper horizontal edge board 28 or $28'$ (FIG. 11) secured to the upper end of the corresponding side wall 24 or $24'$ is nailed to a square 29 to which is pivotally secured the tie 30 or $30'$ the lower end of which engages freely with a reduced clearance the gap i between the shaped members $25a$ and $25b$. It is apparent that after adjusting the tie 30 or $30'$ in the desired position, it is sufficient to tighten the screw provided with the handle 26 so as to lock perfectly the sidewall 24 or $24'$ in its vertical position engaging sideways the bottom 31 of the mould carried by the stay 1 .

All these adjustments are thus performed separately and directly by independent means with the desired accuracy without any difficulty and consequently, in a very speedy manner.

The novel system including the cross-member with its tubular guide 14 and its locking means and the carrier stay sliding in said guide and adapted to be shifted and removed above the latter, forms thus a novel structure of patentable interest.

What I claim is:

1. In an arrangement for staying a structure at two different levels, the combination of a tubular vertical metal stay the upper end of which is adapted to engage one level of the structure, said stay being provided in its lower section with vertically spaced openings, a horizontal metal cross-member mounted to slide freely on the stay in a vertical direction to engage the other level of the structure, a sleeve surrounding the stay underneath the cross-member and independently thereof, a pin releasably engaging a selected opening in the lower section of the stay to hold the sleeve in a corresponding position, and an intermediate member interconnecting the sleeve with the cross-member and including means for progressively adjusting the relative vertical spacing between the sleeve and the cross-member.

2. In an arrangement for staying a structure at two different levels, the combination of a tubular vertical metal stay the upper end of which is adapted to engage one level of the structure, said stay being provided in its lower section with vertically spaced openings, a horizontal metal cross-member mounted to slide freely on the stay in a vertical direction to engage the other level of the structure, a sleeve surrounding the stay underneath the cross-member and independently thereof, a pin releasably engaging a selected opening in the lower section of the stay to hold the sleeve in a corresponding position, and an intermediate member coaxially fitted round the stay and interconnecting the sleeve with the cross-member and including means for progressively adjusting the relative vertical spacing between the sleeve and the cross-member.

3. In an arrangement for staying a structure at two different levels, the combination of a tubular vertical metal stay the upper end of which is adapted to engage one level of the structure, said stay being provided in its lower section with vertically spaced openings, a horizontal metal cross-member mounted to slide freely on the stay in a vertical direction to engage the other level of the structure, a sleeve surrounding the stay underneath the cross-member and independently thereof, a pin releasably engaging a selected opening in the lower section of the stay to hold the sleeve in a corresponding position, and an intermediate member coaxially fitted round the stay, threadedly engaging the outer surface of the sleeve and supporting the cross-member at a level depending on the amount of engagement between said intermediate member and the sleeve.

4. In an arrangement for staying a structure at two different levels, the combination of a tubular vertical metal stay the upper end of which is adapted to engage one level of the structure, said stay being provided in its lower section with vertically spaced openings, a horizontal metal cross-member mounted to slide freely on the stay in a vertical direction to engage the other level of the structure and provided at least to one side of the stay with a longitudinal slot, a slider slidably engaging said slot, means for locking the slider in said slot in a position for which said slider serves as a lateral stop for the structure, a sleeve surrounding the stay underneath the cross-member and independently thereof, a pin releasably engaging a selected opening in the lower section of the stay to hold the sleeve in a corresponding position, and an intermediate member interconnecting the sleeve with the cross-member and including means for progressively adjusting the relative vertical spacing between the sleeve and the cross-member.

5. In an arrangement for staying a structure at two different levels, the combination of a tubular vertical metal stay the upper end of which is adapted to engage one level of the structure, said stay being provided in its lower section with vertically spaced openings, a horizontal metal cross-member mounted to slide freely on the stay in a vertical direction to engage the other level of the structure and provided at least at one end with a forked section with a tie held elastically between the sides of the forked section and extending obliquely into lateral engagement with the stayed structure, a sleeve surrounding the stay underneath the cross-member and independently thereof, a pin releasably engaging a selected opening in the lower section of the stay to hold the sleeve in

a corresponding position, and an intermediate member interconnecting the sleeve with the cross-member and including means for progressively adjusting the relative vertical spacing between the sleeve and the cross-member.

- 5 6. In an arrangement for staying a structure at two different levels, the combination of a tubular vertical metal stay the upper end of which is adapted to engage one level of the structure, said stay being provided in its lower section with vertically spaced openings, a horizontal metal cross-member mounted to slide freely on the stay in a vertical direction to engage the other level of the structure, a tapped sleeve rotatably surrounding the stay underneath the cross-member and independently thereof, a pin releasably engaging a selected opening in the lower section of the stay to hold the sleeve in a corresponding position, and an intermediate member coaxially and slidably fitted over the stay and rigid with the cross-member and threadedly engaging the outer surface of the sleeve.
- 10 7. In an arrangement for staying a structure at two different levels, the combination of a tubular vertical metal stay the upper end of which is adapted to engage one level of the structure, said stay being provided in its lower section with vertically spaced openings, a horizontal metal cross-member mounted to slide freely on the stay in a vertical direction to engage the other level of the structure, a sleeve surrounding the stay underneath the cross-member and independently thereof, a pin releasably engaging a selected opening in the lower section of the stay to hold the sleeve in a corresponding position, and an intermediate member interconnecting the sleeve with the cross-member and including means for progressively adjusting the relative vertical spacing between the sleeve and the cross-member, a tubular support in which
